UNITED STATES PATENT OFFICE.

FRANK ELLISON BEST, OF SEATTLE, WASHINGTON, ASSIGNOR TO FRANK E. BEST, INC., OF SEATTLE, WASHINGTON, A CORPORATION OF WASHINGTON.

MORTISE LOCK.

Application filed June 7, 1923. Serial No. 643,962.

To all whom it may concern:

Be it known that I, FRANK ELLISON BEST, a citizen of the United States, residing at Seattle, in the county of King and State of Washington, have invented a new and useful Mortise Lock, of which the following is a specification.

My invention relates to improvements in pin tumbler mortise locks and the object 10 of my improvement is to provide a pin tumbler mortise lock of the cabinet type that may be successfully applied to relatively thin doors.

In the application of pin tumbler locking structure to locks of the mortise type 15 it is common practice on heavy locks for doors of considerable thickness to provide a threaded opening in the secondary lock housing that contains the latch mechanism 20 and, in assembling, to screw the lock core that contains the pin tumbler structure into said threaded opening after the secondary mechanism is inserted into the mortise in the door and to then lock said core 25 against turning by a screw that is operated from the front edge of the door and is rendered inaccessible when the door is closed.

This method of application is not adaptable 30 on thin doors of the cabinet type because the secondary lock housing is, of necessity, made from light material that does not afford sufficient strength to permit attachment in this manner, and further, 35 because there is not sufficient room for the locking screw in thin mortise locks of this type.

The present invention makes possible the 40 adaptation of a pin tumbler locking structure to a thin mortise lock of this nature by providing a lock having a core case from which the core may be removed, and, by providing means within the core case that is accessible only when the lock core is removed 45 for securing the core case to the secondary lock housing. The removable core thus makes possible a structure that permits the use of pin tumbler mechanism in a thin mortise lock of this nature and the use of a pin tumbler mechanism makes 50 possible the carrying out of a one key system in which an individual needs only one key to operate any number of different locks.

55 With the above and other objects in

view, the invention consists in the novel construction, adaptation and combination of parts as will be more clearly hereinafter described and claimed.

In the accompanying drawings Figure 1 60 is a fragmentary view in elevation showing the edge of a door in which a pin tumbler mortise lock constructed in accordance with my invention is installed.

Fig. 2 is a fragmentary view in elevation 65 showing a portion of the side of the same door.

Fig. 3 is a detached view in side elevation 70 of the mortise lock with the lock core removed.

Fig. 4 is a sectional view substantially on broken line 4—4 of Fig. 3.

Figs. 5, 6 and 7 are detached perspective views of the secondary lock or latch housing, the lock core housing, and the lock core 75 respectively as said three parts might appear if detached and moved apart a short distance from each other.

Referring to the drawings, throughout 80 which like reference numerals designate like parts, 8 designates a relatively thin door in which this lock is installed said door being prepared for the reception of the lock by providing in the same a cavity or mortise of rectangular cross section that extends 85 from the front edge of the door rearwardly and is of substantially the shape indicated by dotted lines in Fig. 2 and by boring from the side of the door a hole as indicated by dotted lines in Fig. 1 that intersects said 90 mortise cavity.

This lock comprises three distinct parts, 95 namely, a latch housing or secondary lock mechanism, Fig. 5, a lock core case or housing, Fig. 6, and a lock core, Fig. 7.

The secondary lock mechanism proper, 100 which is not herein disclosed but which may be of any desired construction, is disposed within a housing 9 of relatively thin rectangular shape that is secured to a front plate 10 which is provided with suitable holes 11 through which screws 12 may be inserted to secure the same to the door 8. An opening 13 is provided in one side of the housing 9.

A core case 14 preferably cylindrical on the exterior and provided with an internal recess 15 of figure 8 cross sectional shape is adapted to be secured to the side of the secondary housing 9 by screws 16 that screw 110

into nuts 17 within the inside of such housing, see Fig. 4. The nuts 17 are preferably permanently fastened within the housing 9,

A lock core 18 having an end flange 19 is arranged to be removably locked within the recess 15 of the core case 14, said removable lock core affording access to the screws 16 when removed and preventing access to said screws when it is inserted. The screws 16 are located on opposite sides of the figure 8 recess 15 and the flange 19 on the core covers the heads of such screws when the core is inserted in the core case.

In installing this lock, the door is mortised to receive the secondary housing 9 and plate 10 and a hole of the same diameter as the exterior of the core case 14 is bored to intersect the mortise at the proper location. The secondary housing is then inserted in the mortise and the core case 14 with the core removed is inserted in the hole in the side of the door and securely fastened to the housing 9 by means of the screws 16. The lock core 18 may then be inserted and locked within the core case 14 thereby protecting the heads of the screws 16 and making it impossible to remove said screws without first removing the lock core.

The screws 16 constitute the only means needed for securing the core case 14 to the housing 9 and the use of said screws for this purpose is made possible by the provision of a lock core that is readily removable from the core case.

35 The secondary housing 9, in a thin mortise lock of this nature is not strong enough to permit a lock core to be screwed thereto and no room is afforded in said secondary housing for the provision of locking screws that are accessible from the edge of the door or drawer into which the lock is mortised thus making it practically impossible to adapt pin tumbler locks that depend on this method of securing the lock core to the lock 40 housing to a thin cabinet type mortise lock.

The core case 14 is open at the inner end and is arranged to register with the opening 13 in the secondary housing 9 when it is secured thereto.

50 The foregoing description and accompanying drawings clearly disclose what I now consider to be a preferred embodiment of my invention, but it will be understood that changes in the same may be resorted to within the scope of the following claims.

I claim:

1. In a mortise lock, a secondary lock housing, a core case, a lock core arranged for removal from said core case and means accessible only when said core is removed for securing said core case to said secondary lock housing.

2. A mortise lock embodying a secondary lock housing arranged to be inserted in a mortise, a core case, a lock core arranged to be removed from said core case and means accessible only from the interior of said core case for securing said core case to said secondary lock housing.

3. A mortise lock embodying a relatively thin flat secondary lock housing having an opening in one side, a core case arranged to fit against the side of said secondary lock housing and covering said opening, screws accessible only from the interior of said core case for securing said core case to said secondary lock housing; and a lock core removable from said core case to afford access to said screws.

4. In a mortise lock, a relatively thin flat secondary lock housing adapted to be inserted in a mortise, a core case arranged to fit against the side of said secondary lock housing, said core case having a recess of figure 8 cross sectional shape, two screws disposed on opposite sides of said recess for securing said core case to said secondary lock housing and a lock core arranged to be locked within said core case and removable therefrom to afford access to said screws. 90

5. In a mortise lock the combination with a door having two intersecting mortise holes, of a secondary lock housing arranged to be inserted into one of said holes, a recessed core case arranged to be inserted into the other of said holes, a lock core arranged to be removably locked within said core case and means accessible only when said lock core is removed for securing said core case to said secondary lock housing. 100

6. In a mortise lock, a secondary lock housing, a core case, screws extending from the outer end of said core case inwardly for securing said core case to said secondary lock housing, a lock core removable from said core case and a face plate on said lock core arranged to cover the heads of said screws when said lock core is within said core case. 105

FRANK ELLISON BEST.
